DESIGN FOR A BOTTLE

Monroe Harrison, Chicago, Ill.

Application June 4, 1936, Serial No. 63,031

Term of patent 3½ years

To all whom it may concern:

Be it known that I, Monroe Harrison, a citizen of the United States, residing at Chicago, in the county of Cook and State of Illinois, have invented a new, original, and ornamental Design for a Bottle, of which the following is a specification, reference being had to the accompanying drawing, forming a part thereof.

In the drawing:

Figure 1 is a plan view of a bottle embodying my design; and

Figure 2 is a front or side view of the bottle.

The bottle is of an orange color, but color shading has been omitted from the drawing because such shading would tend towards confusion in view of the surface ornamentation, or stippling of the bottle.

I claim:

The ornamental design for a bottle substantially as shown and described.

MONROE HARRISON.
